UNITED STATES PATENT OFFICE

103,887

DESIGN FOR A COMBINATION CONTAINER FOR COSMETIC PREPARATIONS

Benjamin F. Conner, West Hartford, Conn., assignor to Colt's Patent Fire Arms Manufacturing Co., Hartford, Conn., a corporation of Connecticut

Application February 11, 1937, Serial No. 67,599

Term of patent 14 years

To all whom it may concern:

Be it known that I, Benjamin F. Conner, a citizen of the United States, residing at West Hartford, in the county of Hartford and State of Connecticut, have invented a new, original, and ornamental Design for a combination container for Cosmetic Preparations, of which the following is a specification, reference being had to the accompanying drawing.

Of the drawing:

Fig. 1 is a plan view of a combination container for cosmetic preparations embodying my new design.

Fig. 2 is a side view thereof.

The stippled and unstippled portions of the drawing are intended to represent different colors, but not any particular colors. Although different colors are represented, I nevertheless regard the shape or configuration of the container as constituting the dominant feature of my design.

I claim:

The ornamental design for a combination container for cosmetic preparations as shown and described.

BENJAMIN F. CONNER.
